HYDRAULIC CONTROL MECHANISM

Warren P. Willett, Takoma Park, Md., assignor
to Vickers, Incorporated, Detroit, Mich., a cor-
poration of Michigan

Application February 14, 1941, Serial No. 378,920

18 Claims. (Cl. 60—53)

This invention relates to a hydraulic control mechanism.

It is an object of the present invention to provide a control mechanism for a hydraulic circuit in which movement is started by the shifting of a hand lever and stopped automatically by a control mechanism at a predetermined point in the movement of the device being controlled. The invention contemplates a servo-control used in combination with the control device so that the speed of the member being controlled may be regulated by the operator.

Another feature of the invention has to do with an automatic means for venting the operating lines at the completion of a cycle thereby obviating any tendency for the output shaft to creep, due to imperfect centering of the variable displacement pump which is used in the system.

A further object of the invention is to provide a hydraulic circuit which may be stopped, started, or reversed at any point in the cycle of the operation. Provision is also made for the operation of the control elements by hand in the event that there is pressure failure in the servo-control mechanism.

Other objects and features of the invention relating to details of the circuit and operating means therefor, will be apparent in the following description and claims.

In the drawings:

Fig. 1 illustrates the circuit of the present invention with the parts in the position which follows the reversal movement after the hand lever has been moved back to neutral.

Fig. 1A is a side view of the brake mechanism shown in Fig. 1.

Fig. 2 shows the circuit with the parts as they would be positioned near the beginning of a forward movement but after the pump has been advanced to its full volume position by the control mechanism.

Fig. 3 shows the circuit at the end of the forward movement before the hand lever has been returned to neutral.

Fig. 4 shows the circuit with the parts in their position near the beginning of a reversing movement but after the pump has been advanced to its full volume position by the control mechanism.

The system as shown is particularly adapted to various types of machinery but is especially suitable for driving ordnance equipment such as ammunition hoists and rammers. The circuit shown is particularly adapted for a rammer and

it will be described in connection with a ramming movement and a retracting movement, although the rammer mechanism is not shown.

The main elements of the circuit include an electric motor 10 which drives a reversible variable pump 11. The pump 11 furnishes liquid under pressure to a hydraulic motor 12 which has an operating shaft 13. A braking wheel 14 is mounted on shaft 13 and a brake shoe 15 is connected to a bellcrank 16 operated by a piston 17.

The elements of the control for the hydraulic circuit include first, a movable member 20 on pump 11 which controls the rate and direction 15 of flow through the pump according to its displacement from center. A valve 21 operated by a hand lever 22 controls the position of a piston 23 which actuates the movable member 20. Hand lever 22 has a ram position as shown and a retracted position. A rod 24 and a spring 25 connect the hand lever with a lever 26 which is connected at one end to the member 20 and the other end to a link 27 and rod 28 leading to the valve 21. A piston rod 29 on piston 23 is connected to the other end of lever 26 and also is connected to a lever 30 which serves as part of an automatic control for decelerating and stopping the motor 12.

Lever 30 is operated by nuts 31 and 32 which 30 thread back and forth on a threaded rod 33 driven by power shaft 13 through bevel gears. The nuts 31 and 32 are notched and slide on a bar 34 to prevent their turning. Rod 33 also has cams 35 and 36 which actuate, respectively, 35 timing valves 37 and 38 in a housing 42. A valve 41 in housing 42 is also arranged to be actuated by the nuts 31 and 32 in a manner which will be described in detail.

Pump 11 is connected to motor 12 by two conduits 45 and 46. Conduit 45 will be under pressure during the ramming stroke while conduit 46 will be under pressure during the retraction stroke. These conduits are connected to the respective ends of the bore in housing 42 by conduits 47 and 48. Valve 41 is so arranged that when either conduit 45 or 46 is under pressure, valve 41 will be shifted by the pressure which passes to the valve housing through conduits 47 and 48. Valve 41 is connected up hydraulically 50 with valves 37 and 38, a port 50 being connected by a conduit 51 to valve 37 and a port 52 being connected by a conduit 53 to valve 38. A center port 55 is connected to a conduit 56. Conduit 56 which may be known as a bypass conduit, passes through a restricted portion 57 of valve

21 and the valve is properly positioned to a bypass valve 58 which is controlled by a cam 59 on rod 29. Conduit 56 is also connected to spring pressed piston 17 of the brake mechanism by a conduit 60 so that when the bypass conduit is blocked by either valve 21 or 58, pressure will build up in the system and release the brake. With the bypass line vented through both valves 21 and 58 as shown in Fig. 1, a spring 61 acting on piston 17 will engage the brake. Conduits 65 and 66 connect respectively, the pressure conduits 45 and 46 with the bypass conduit 56 through check valves 67 and 68.

At the left end of valve 21 a restriction 10 forms a valve which controls conduits 77 and 78 which are connected respectively, with valves 37 and 38. A pilot pump 80, driven by motor 10, directs pressure through pilot line 81 to valve 21 where it may pass a restriction 82 or 83 to conduits 84 or 85 respectively, leading to the opposite sides of piston 23. A branch conduit 86 leads to a spring pressed valve 87 which is normally held in the position shown by pilot pressure. In the event of failure of pilot pressure, valve 87 shifts to the left to bypass lines 84 and 85. A relief valve 88 controls the pilot pressure while valves 90 and 91 connect the pilot line 81 respectively, with lines 45 and 46 of the main circuit. Restrictions 92 and 93, leading to check valves 90 and 91 prevent the diversion of the entire flow of the pilot pump to the main circuit when the main circuit is vented.

In the operation, Fig. 1 illustrates the parts at the end of a reverse movement with the manual lever 22 in neutral position. To initiate a ram or forward movement, the lever 22 is moved ahead, as shown in Figs. 2 and 3. The position of lever 26 at the beginning of the movement is shown in Fig. 3 wherein the valve 21 is shifted so that pilot pressure from line 81 may pass to line 85 and shift piston 23 to the left. During the initial movement of lever 26 it has pivoted at its lower end on the link connected to member 20. As the piston 23 starts to move to the left, lever 26 will pivot about its center mounting thereby returning valve 21 to neutral. Consequently, the piston 23 will move in a follow-up manner in a degree proportional to the displacement of the lever 22 toward the ram position but at the end of the movement of piston 23, the valve 21 will be in neutral position, as shown in Fig. 1. The pump will then deliver to the motor at the capacity at which it is set as shown in Fig. 2 until nut 32 engages lever 30 to move it from its Fig. 2 position to its Fig. 3 position. In the movement of the piston 23 to the left, cam 59 is shifted to the left thereby permitting the valve 58 to drop and close conduit 56 from the tank. Meanwhile, pressure is building up in conduit 45 due to the displacement of the movable member 20. This pressure will react through conduit 47 to shift valve 41 to its extreme right position. The shifting of valve 21 to the left will also block the vent in conduit 56, thereby causing pilot pressure to be built up above piston 17 to release the brake shoe 15. After motion has started, cam 59 will have moved to the left where it allows valve 58 to close and maintain the blocking of the vent in conduit 56. In this manner the subsequent shifting of valve 21 is rendered ineffective as a means of engaging the brake until the recentering of pump 20 has returned cam 59 to open the valve 58. The shifting of valve 41 to the position shown in Fig. 2, blocks the center port 55 and thereby prevents

bypassing of line 56 through either of the valves 31 or 38. As the forward movement progresses, nuts 31 and 32 will shift to the left. Near the end of the cycle, nut 32 will contact the lower end of lever 30 and move the piston 23 and movable member 20 gradually back to neutral position. This position is shown in Fig. 3. Since the spring 25 is provided in rod 24, there will be a force on lever 26 which will shift valve 21 to the left again, as shown in Fig. 3 (provided the control lever is manually held in the "Ram" position shown). Liquid to the right of piston 23 will thus be forced into lines 85 and 81 with check valve 88 taking care of volume displacement. Pressure from line 81 can not shift piston 23 since it is blocked by the nut 32. In the event the control lever is released during the deceleration and stopping action, it will follow the movement of pump 20 to neutral. Nut 31 in traveling to the left, will shift valve 41 slightly to the left to open center port 55 to port 52 in line 53. After this opening, when cam 36 reaches the point where valve 38 is open, as shown in Fig. 3, the pressure in bypass line 56 will be transferred through line 78 to the tank around the restriction 76 in valve 21. This path is shown in Fig. 3. Bypassing of line 56, of course, relieves pressure on the piston 17 and applies the brake. It also relieves any pressure that might remain in lines 45 or 46 due to imperfect centering of the member 20. There will, therefore, be no further movement of the shaft 13.

To effect reversal or retraction, the members are shifted as shown in Fig. 4 with valve 21 being moved first to the right where it will admit liquid from line 81, to the left hand end of the piston 23 and shift it to the right, after which, due to movement of the piston, the valve 21 will be re-centered. During the retraction movement valve 41 is in the extreme left position blocking the center port until at the end of the movement, as shown in Fig. 1, the nut 32 shifts the valve to open the center port to port 50 and valve 37 which will bypass line 56 to line 77 and the tank, thereby stopping the system. At the end of the reversal, the nut 31 will shift the lever 30 back to its upright position, as shown in Fig. 1.

I claim:

1. In a hydraulic variable speed transmission system for driving a load device, a variable speed transmitting including a pump member and a motor member, a pressure responsive movable part on one of said members for varying the output speed and the direction of the transmission, lines connecting said pump member and motor member, each adapted to serve alternately as pressure and return lines, control means for the movement of said transmission comprising a manual control member, hydraulic means responsive to movement to said member for shifting said movable part to a position whereby pressure is directed through said transmission, and means responsive to a predetermined movement of said motor for shifting said movable part gradually back to a neutral position independently of said hydraulic means.

2. In a hydraulic mechanism, a reversible variable delivery pump with a movable control head for volume and directional control, a reversible motor to be driven by pressure from said pump, lines connecting said pump and motor, each adapted to serve alternately as pressure and return lines, control means for the movement of said motor comprising a manual control mem-

ber having neutral and actuating positions, hydraulic means responsive to movement of said member for shifting said pump control head to a position whereby pressure is directed to said motor, means responsive to a predetermined movement of said motor for shifting said head gradually back to a neutral position independently of said hydraulic means, means responsive to said motor movement to bypass said lines after predetermined movement to prevent further movement of said motor when said manual control member remains in actuating position, and additional means for bypassing said lines when said control member is in neutral position.

3. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position, and additional means responsive to said motor movement to bypass said lines to prevent further movement of said motor, said additional means being responsive to pressure in one or the other of said lines and arranged to be reset by said pressure at the start of a cycle of movement of said motor.

4. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position comprising a rotating shaft driven by said motor, nuts on said shaft, means for holding said nuts against rotation but permitting axial movement relative to the shaft, a lever to be actuated by one or the other of said nuts, and means connecting said lever and said control head whereby upon predetermined movement of said motor, said control head will be moved back to a neutral position.

5. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position comprising a rotating shaft driven by said motor, nuts on said shaft, means for holding said nuts against rotation but permitting axial movement relative to the shaft, a lever to be actuated by one or the other of said nuts, means connecting said lever and said control head whereby

upon predetermined movement of said motor, said control head will be moved back to a neutral position, and additional means responsive to said motor movement to bypass said lines to prevent further movement of said motor.

6. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position comprising a rotating shaft driven by said motor, nuts on said shaft, means for holding said nuts against rotation but permitting axial movement relative to the shaft, a lever to be actuated by one or the other of said nuts, means connecting said lever and said control head whereby upon predetermined movement of said motor, said control head will be moved back to a neutral position, and additional means responsive to said motor movement to bypass said lines to prevent further movement of said motor, said additional means being responsive to pressure in one or the other of said lines and arranged to be reset by said pressure at the start of a cycle of movement of said motor.

7. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position, additional means responsive to said motor movement to bypass said lines to prevent further movement of said motor, comprising conduits connecting said lines and a series of valves in said conduits including a slow moving valve actuated by said motor and a fast moving valve actuated by said motor, and means connecting said valves and said motor whereby, upon a predetermined movement of said motor, said slow valve will have shifted to open said bypass lines and, at a predetermined point in the rotation of said motor, said fast valve will also be moved to open said bypass lines thereby preventing further movement of said motor.

8. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position comprising a rotating shaft driven by said motor, nuts on said shaft,

means for holding said nuts against rotation but permitting axial movement relative to the shaft, a lever to be actuated by one or the other of said nuts, means connecting said lever and said control head whereby upon predetermined movement of said motor, said control head will be moved back to a neutral position, additional means responsive to said motor movement to bypass said lines to prevent further movement of said motor, comprising conduits connecting said lines and a series of valves in said conduits including a slow moving valve actuated by said motor and a fast moving valve actuated by said motor, and means connecting said valves and said motor whereby, upon a predetermined movement of said motor, said slow valve will have shifted to open said bypass lines and, at a predetermined point in the rotation of said motor, said fast valve will also be moved to open said bypass lines, thereby preventing further movement of said motor.

9. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting said head gradually back to a neutral position comprising a rotating shaft driven by said motor, nuts on said shaft, means for holding said nuts against rotation but permitting axial movement relative to the shaft, a lever to be actuated by one or the other of said nuts, means connecting said lever and said control head whereby upon predetermined movement of said motor, said control head will be moved back to a neutral position, additional means responsive to said motor movement to bypass said lines to prevent further movement of said motor, comprising conduits connecting

said lines and a series of valves in said conduits including a slow moving valve actuated by said motor and a fast moving valve actuated by said motor, and means connecting said valves and said motor whereby, upon a predetermined movement of said motor, said slow valve will have shifted to open said bypass lines and, at a predetermined point in the rotation of said motor, said fast valve will also be moved to open said bypass lines, thereby preventing further movement of said motor, said slow valve being responsive to pressure in one or the other of said lines and being reset by said pressure at the start of a cycle of movement of said motor.

10. In a hydraulic mechanism, a reversible variable delivery pump with a movable control head for volume control, a reversible motor to be driven by pressure from said pump, lines connecting said pump and motor, each adapted to serve alternately as pressure and return lines, control means for the movement of said motor comprising a manual control member, hydraulic means responsive to movement of said member for shifting said pump control head to a position whereby pressure is directed to said motor, means responsive to a predetermined movement of said motor for shifting of said head gradually back to a neutral position, additional means responsive to said motor movement to bypass said lines to prevent further movement of said motor, comprising conduits connecting said lines and a series of valves in said conduits including a slow moving valve actuated by said motor and a fast moving valve actuated by said motor, and means connecting said valves and said motor whereby, upon a predetermined movement of said motor, said slow valve will have shifted to open said bypass lines and, at a predetermined point in the rotation of said motor, said fast valve will also be moved to open said bypass lines thereby preventing further movement of said motor, said slow valve being responsive to pressure in one or the other of said lines and being reset by said pressure at the start of a cycle of movement of said motor.

WARREN P. WILLETT.
